(57) **CLAIM**

The ornamental design for a disc jockey controller, as shown and described.

DESCRIPTION

FIG. 1 is a top, front, and left perspective view of a disc jockey controller showing our design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken line in the figure drawings represents unclaimed environment only and forms no part of the claimed design; the dash-dot broken line in the figure drawings represents unclaimed boundary of the claimed design.

1 Claim, 5 Drawing Sheets
